G. X. WENDLING

POLE BASE CONSTRUCTION

Filed July 5, 1922

FIG. 2

INVENTOR.
George X. Wendling
BY
Cicero & Totten
ATTORNEYS.

UNITED STATES PATENT OFFICE.

GEORGE X. WENDLING, OF SAN FRANCISCO, CALIFORNIA.

POLE-BASE CONSTRUCTION.

Application filed July 5, 1922. Serial No. 572,929.

To all whom it may concern:

Be it known that I, GEORGE X. WENDLING, a citizen of the United States, residing at the city and county of San Francisco and 5 State of California, have invented certain new and useful Improvements in Pole-Base Constructions, of which the following is a specification.

Poles or posts employed primarily in the 10 supporting of wires, cables or other connecting means are preferably constructed of wood with their butts or bases inserted a short distance in the ground. The mounting of the poles in this manner has demonstrated that the action of the elements on 15 the pole or post for a short distance both above and below the surface of the soil soon rots the pole or post at this point, and the same having become weakened often breaks 20 at the ground under the weight of the load supported.

My invention relates to the construction 25 of a pole base, preferably prior to inserting the pole in the ground, whereby a preservative solution is contained within the heart 30 of the pole base, and the pole surface, at a point for a short distance above and below the ground, is protected by an absorbent covering adapted to contain a preservative solution, which covering is in turn protected 35 and the solution thus prevented from evaporating, and which second covering is in turn reinforced by a metallic wire structure.

With the above mentioned and other objects in view, the invention consists in the 40 novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the 45 invention.

To more clearly comprehend the invention, reference is directed to the accompanying drawings, wherein—

Fig. 1 is a view in elevation of a pole base 50 or butt partly in broken section, illustrating the preferred embodiment of my invention.

Fig. 2 is a view in elevation of a pole illustrating the protected butt or base in full elevation.

Fig. 3 is a sectional view on the line B—B

of Fig. 1, illustrating the thimble reinforcing the central bore.

Referring more particularly to the drawings wherein like characters of reference designate corresponding parts—1 indicates 60 a channel or bore formed centrally of the butt or base of the pole 2 and the same extends thereinto to a point preferably above the point of insertion of the pole butt or base in the ground when the same is in use. 65 The bore or channel is surrounded at the extreme lower end of the pole by a metallic thimble 3 which forms a reinforcement surrounding the bore and prevents the splitting of the base of the pole when the plug 4 to 70 close the lower end of said bore 1 is driven into position. A lateral channel 5 is bored transversely into the pole at a point above the ground and intersecting the upper end of the bore 1, and said channel 5 affords a 75 means for forcing into said bore or channel 1 any desired preservative fluid and which channel affords a reservoir for holding said fluid, permitting the seepage thereof outwardly through the wood fibers. 80

The periphery of the pole base is preferably turned or annularly recessed as at 6 and within said recess is positioned a filling of absorbent 7, the outer layer of which extends beyond the upper and lower edges of the recess 6. The absorbent is preferably felt, moss or the like, and the same is saturated with any suitable preservative. Around this absorbent is positioned a wrapping of thin wood, either in the form of staves 8 or a continuous veneer, Fig. 1 illustrating staves and Fig. 2 a continuous veneer 8', and the same projects beyond the upper and lower edges of the turned recess 6. 85

The wood protecting sheath is maintained in position and is protected from damage by the spiral wrapping or wire 9, one end of which is anchored as at 10 in the pole base and the remainder of which is tightly coiled spirally about the protecting sheath to a point near its upper end where the coils contact, forming a continuous wire surface 11 extending over and beyond the upper edge of the sheath 8, affording a means for shedding water which during storms may flow 100 down the pole. 95

If desirable, the channel 5 may be supplied with a valve closure, not shown, and the preservative fluid may be pumped 105 therein under pressure and the valve closed. 110

It will be observed that the absorbent 7 saturated with the preservative prior to positioning within the channel 6, will retain the moisture, and thus protect the surface 5 of the pole base from the action of the elements.

By annularly recessing the pole at 6, which recess extends above and below the surface of the ground into which the pole butt is 10 inserted, I remove the soft surface of the pole, which is easily affected by the elements and rapidly decays.

My improved construction enables the seepage of the preservative fluid from the 15 reservoir 1 outwardly through the pole to be caught by the absorbent 7 and thus maintain said absorbent saturated with the preservative fluid, thus protecting the surface 20 of the pole from decaying by the action of the elements.

Having thus described my invention, what I claim as new and desire to secure by Letters Patent of the United States is:—

1. In combination with a pole provided 25 with a longitudinal channel in its butt end forming a reservoir for containing a body of wood preservative fluid, said channel ter-

minating at its upper end in a filling inlet opening at one side of the pole, a body of absorbent for surrounding the pole butt 30 within the length of said channel, and means surrounding said body of absorbent for protecting the same and retaining it in position about the pole whereby the preservative seeping outwardly through the pole butt 35 from said reservoir will maintain said absorbent moist.

2. In combination with a pole provided with a longitudinal channel formed substantially centrally of its butt end and affording a reservoir for containing a body of wood preservative fluid, said channel terminating at its upper end in a filling inlet opening at one side of the pole, a peripheral absorbent receiving recess formed annularly 45 of the pole about said reservoir, an absorbent within said recess and means for protecting and retaining said absorbent within said recess whereby the preservative seeping outwardly through the pole from said 50 reservoir will maintain said absorbent moist.

In testimony whereof I have signed my name to this specification.

GEORGE X. WENDLING.
